UNITED STATES PATENT OFFICE.

RICHARD TJADER, OF NEW YORK, N. Y.

AUTOMATIC MEANS FOR LOWERING LIFE-BOATS.

1,116,956.

Specification of Letters Patent. Patented Nov. 10, 1914.

Application filed January 5, 1914. Serial No. 829,824.

To all whom it may concern:

Be it known that I, RICHARD TJADER, a citizen of the United States, and a resident of the city of New York, borough of Manhattan, in the county and State of New York, have invented a new and Improved Automatic Means for Lowering Life-Boats, of which the following is a full, clear, and exact description.

10 This invention relates to ships and has particular reference to means for supporting life boats on the decks of ships and also for the rapid manipulation of the life boats either for hoisting or launching, more particularly the latter.

15 Among the objects of the present invention, distinguishing it from said previous device, is to so improve the mechanism as to provide for the increased facilities for entering the life boat while in its normal position on shipboard and to increase the safety of the passengers while being lowered therein.

20 Another object of this invention is to economize the space which may be used for the storage or support of life boats, and by special construction of supporting means I provide accommodation for two life boats, one above the other, said boats being adapted to be launched in succession from or by the same pair of davits.

25 The foregoing and many other objects of the invention will hereinafter be more fully described and claimed and illustrated in the 30 drawings forming a part of this specification in which like characters of reference indicate corresponding parts in all the views, and in which—

35 Figure 1 is an end elevation of the improvement; Fig. 2 is a rear elevation of the same; Fig. 3 is a plan view; Fig. 4 is a vertical section through the cable drum; Fig. 5 is a detail side view of a special form of gearing employed for controlling the operation of the highest drum; and Fig. 6 is a modification of the supporting chair.

40 The several parts of the device may be made of any suitable materials, and the relative sizes and proportions, as well as the 45 general design of the mechanism, may be varied to a considerable extent without departing from the spirit of the invention hereinafter more fully set forth and specifically claimed.

50 Referring more particularly to the drawings, I show at 10 and 11 standards fixed in

any suitable stationary position and by any suitable means to the deck of a ship. Said standards are preferably of angle or channel construction, and each of them is shown as 50 being supported in position by frame and brace members including a base 12, ogee-shaped bars 13, and any suitable number or arrangement of diagonal braces 14, 15 and 16. The ogee bars are secured at their lower 55

ends to the outer ends of the base members 12 by means of angle brackets and at their upper ends connected to the standards well up toward their tops. The shape of the bars 13 contributes not only to their appearance 60 but to the facility for movement of the boat into and out of normal position. The diagonal braces 14 are secured at one end to the brackets and at their other ends to the standards between the lower ends thereof and the 65

point of connection of the ogee bars. The bars 15 serve not only as additional stiffening and strengthening means for the supporting structure, being connected at one end to a corner bracket 18 at the foot of 70 the standards and at their upper ends to the middle portion of the ogee bars, but they also serve as means for steadyng and guiding the davit arms 19 while the boat is being launched or hoisted, as will be described 75

further below. The davit arms are supported upon curved supports 21 adapted to roll through a limited amount of movement upon the base members 12 as indicated in full and dotted lines in Fig. 1, but the supports in 80 this instance, instead of being circular arcs or segments, are rather elliptical, whereby when the davit arms are moved outwardly to lower a boat the special elongated form 85

of the supports causes them to impart to the 90 boat a lifting effect relative to the simple rolling effect of segmental supports as heretofore used. In this instance the arms are received and held in stable steady position throughout the major portion of their length 95 within the standards 10 and 11. Each of the segments 21 is shown provided with a stud 22 movable in and along a slot 15' formed in a diagonal brace 15. The stud 22 moves along the slot until the davit support 21 rolls 100

to and is supported upon its outer point. In order to relieve the shock which might, under certain circumstances, result from the stopping of the davit arms on their outward and downward movement, I provide cushioning devices 23 shown in the form of 105 springs connected to the braces 14 and

110

adapted to be impinged by the studs 22. I also provide stop pins 15^a which may be employed in connection with any one of a series of holes along braces 15 for the purpose of supporting the boat temporarily at any desired intermediate position, whereby crushing of the boat during launching on heavy seas may be prevented.

The main support for the boat consists of a chair 24 having a base 25 and a hook-shaped adjustable upper end 26 adapted to engage over or receive the gunwale 27 of the life boat. The keel 28 engages and is supported by one or more lifting cam members 29 secured to a rock shaft 29^a, and the position of which is controlled by means of a lever 30. The controlling lever 30 for the rock shaft 29^a may be manipulated in any desired manner from the upper side of the structure as, for instance, through a hand lever 59 pivoted upon the frame which supports the main power drum. The throw of the cams 29 is made effective to lift the boat when the latter is being hoisted so as to cause the gunwale of the boat to come snugly up within the hooks 26 and 26^a, the boat keel being carried by the cams by virtue of a lug 31 on each cam engaging with the outer face of said keel. The hooks 26^a are secured to the standards. The life boat is steadied and held securely in its normal position by reason of dogs 32 pivoted upon any suitable points of the structure, and having their outer ends coöperating snugly with the inner face of the keel. When the boat has been lowered, the dogs 32 rest upon cam flanges or extensions 32^a ready to be engaged by the keel on the subsequent hoisting of the boat, and said dogs are elevated by said extensions and by the keel automatically while the hoisting of the boat is being completed.

The power means for controlling the life boat in connection with the mechanism above described includes a pair of cables 35 which are each connected at one end at 36 to the upper end of the adjacent davit arm. A sheave 37 is journaled in said arm adjacent the point 36 and the traveling pulley 38, having connection by chains 39 in any suitable manner for quick detachment of the boat after it is launched, operates in the bight of cable 35' below the sheave 37. The cable 35 from the sheave 37 passes inwardly and over a sheave 40 journaled at the upper end of the adjacent standard 10 or 11, passes thence downwardly along the rear wall of the channel member constituting said standard, to a direction pulley 41 near the bottom of the standard, and thence to a drum 42 connected to a shaft 43 herein shown as vertically arranged, but which might be otherwise arranged, if desired, and connected to suitable gearing 44 and 45. By providing two parts 42^a and 42^b for the drum and

mounting them upon the shaft 43 in such a manner as to release either of them for rotation independently of the other, I provide a means whereby the life boat may be leveled even though the ship may be sinking with one end ahead of the other. For instance, should a ship be sinking stem foremost, the life boat being held normally by the supporting means in a position parallel to the axis of the ship would be in an inclined position. I therefore so arrange that the stern end of the life boat may be lowered by paying out one of the drum sections, while the other remains stationary, so as to level the life boat. By lifting up on either of the drum sections, either by a hand spike or lever of any convenient nature, the drum section so lifted may be set free from the key or polygonal portion 42^c of the shaft which normally makes driving connection between the shaft and drum, and the lifting means for the drum may serve not only as a means for detaching the drum in the way described but also as a brake for controlling the speed or extent of such independent rotation of the section, but when the lever is removed the drum section so detached from the shaft will automatically connect itself through said key or shouldered portion.

As indicated especially in Fig. 4, the disk 42^d is secured to the shaft 43 between the upper and lower drum parts 42^a and 42^b and close to the shouldered part 42^c. This disk is normally spaced from the lower drum part 42^b and serves as a brake element in connection with the upper end of the drum part 42^b when the latter is lifted out of engagement with its shouldered part 42^c. The upper drum part is adapted to coöperate in a similar manner with the worm wheel 44. By this means the rotation of either drum part may be precisely controlled by the means above described.

The gearing may be of any suitable type for power efficiency and safety, but shown herein as being worm gearing of substantially 45 degrees pitch, whereby, upon rotation of the worm 45 through a power shaft 46, the worm wheel 44 may be rotated powerfully to wind up the cables upon the two parts of the drum, and yet the pitch of the worm is such that it will not constitute a lock preventing the automatic unwinding of the cables from the drum. At this point it is observed that one of the important features of novelty and advantage in this invention is the provision for automatic lowering of the boat even though the last man is leaving the ship in such boat. The rotation of the shaft 46 may be controlled in any suitable manner, and to illustrate such controlling means I show a wheel 47 having a handle 48 whereby it may be rotated to wind up the cables, such wheel also serving as a brake wheel to control the speed at which

the boat is being lowered. The brake shoe 49 is pivoted at 50 upon the frame in which the drum is mounted, and the lever 51 extending from said shoe has connected to its opposite end a line 52 leading into the boat, whereby an occupant of the boat may have control of the speed of descent of the boat. A portion of the line 52 between the brake and the boat is carried in a keeper or eye 53 in the edge of the deck 54.

Each of the pulleys 38 is carried in a shackle 55 having gudgeons 56 supported normally upon a pair of hooks 57 constituting a part of the upper end of the adjacent 15 davit arm. It will be noted, therefore, that the cables 35, by virtue of the hooks 57 and the means for supporting the keel of the boat, are always normally relieved from the weight of the boat. The shackles 55 remain 20 in engagement with said hooks, due to the shape of the hooks and the fact that there is always a certain amount of strain upon the cables 35 after the boat leaves its normal supports, until the davit arms pass 25 well outwardly or until stopped in the manner above described. From this time onward until the boat is fully launched, the weight of the boat is sustained through the pulleys 38 upon the two parts of the cables 30 constituting the bights 35', the speed at which the cables pay out from the drum 42 being determined by the action of the brake above described.

By the provision of the herein described means for the easy and safe manipulation of life boats even when fully loaded, I am able to load such boats while held in normal position upon the deck of the ship instead of following the usual practice of loading 40 them from the side of the ship while the boats are being held in an unstable position in midair. Either the chair or the standards 10 and 11 may be utilized as a means for assisting passengers to enter the boat. 45 For this purpose I show ladders 58 arranged as a part of the permanent stationary structure and of sufficient height and suitably located so that the passengers may utilize them to enter the boat.

Having thus described the preferred construction of mechanism, the operation may be briefly summarized as follows: With the parts in the normal position and with the boat loaded, the operator will release the 55 lever 59 from the arm 30 so as to cause the cams 29 to swing outwardly, releasing the hold of the lugs 31 upon the keel. A slight pull on the part of the operator is sufficient to throw the cams around or beyond the axis thereof, setting the boat free to gravitate, 60 automatically releasing itself from the hooks 26 and causing the davit arms 19 and 20 to swing or roll outwardly and downwardly by virtue of the supports 21. If the operator remains on deck he may control the

speed of descent of the boat by applying friction to the brake wheel 47, or such control may be had from the life boat, if desired, through the line 52. The peculiar arrangement of the main cables 35 upon the drum 42 provides that the least amount of strain upon the shaft 43 and its bearings will result, the two cables acting upon opposite sides of the axis of the drum, and the cables paying out or winding on the drum in unison. Upon the hoisting or restoring to position of the boat, the arms 19 and 20 will remain in the outward position until the shackles 55 strike the ends of the arms, and then the subsequent draft upon the cables 58 will insure the guidance of the shackles along the slots leading to the hooks and the proper seating thereof of the hooks and the subsequent lifting of the arms into the normal position. Upon the swinging of the lever 30 so as to hoist the boat keel, as above described, and the locking of said lever by the lever 59, the boat will be maintained in firm and secure position, being supported from above upon the shackles and arms and from below upon the cams between the lugs 31 and the dogs 32. This arrangement, furthermore, provides that the boat may be manipulated by connections at any desired distance from the ends of the boat, a matter of considerable importance when it is considered that boats of various lengths are met with, and for other reasons. Each of the cams or lifting members 29 is preferably provided with a lug 60 opposite and spaced inwardly from the above described lug 31. The purpose of the lugs 60 on the several cam members is to assist in steady- 90 ing the keel of the boat supported upon said members, but more particularly it is to provide a means for positively starting the boat on its downward automatic movement in the event of the ship having a list and the boat being located on the upper side of the ship. In other words, when the life boat is heavily loaded and lying hence with its center of gravity well inward from the vertical plane coincident with the axis of the rock shaft 29^a, some means is necessary for initiating the downward movement of the life boat so as to throw it outward and to enable the keel to glide downward below or beyond said rock shaft. 105

As shown in the preferred form of the invention, the drum 42 is housed within the base 25 of the chair 24 and far enough inwardly to accommodate a second or auxiliary boat beneath the primary boat at the top of the device. After the upper or primary boat has been launched in the manner above set forth, the secondary boat may be loaded and launched by the use of the same davits. Said secondary boats is normally supported upon a carriage 61 having antifriction rollers 62 operating along and beneath channel mem- 115 120 125 130

bers 63 leading toward the edge of the ship. Said secondary boat is supported on the carriage and may be delivered therefrom to initiate the launching by means of devices similar to those already described in connection with the primary boat, said devices including hooks 26, actuating cams 29 and dogs 32. The special advantage of the elliptical form of curved supports 21, in addition to the steadyng of the first part of the launching operation, is to insure a sufficient clearance for the primary boat as it passes above or over the edge of the secondary boat while the latter remains in its normal position by virtue of the lifting effect of the davit arms as they roll outwardly from normal position causing the points of contact thereof with the base members to shift from their longer to their shorter radii. Said carriage 61 with the secondary boat supported thereon may be retained in its normal position directly beneath the primary boat by any suitable means. For instance, I may use a chuck or a removable pin 64 at either or both ends of the carriage.

In Fig. 6 I show a modification of a chair or supporting device which is used especially on freight steamers or the like, where there is ample room for such number of life boats as are required for such service and where a single boat will be accommodated on or in connection with a pair of davits. In this form of the device the drum is located well below the normal position of the boat, providing a more compact arrangement for the operating devices.

Having thus described my invention, I claim as new and desire to secure by Letters Patent:—

1. In automatic means for lowering life boats, the combination with stationary standards, base and bracing means for said standards, a pair of davit arms including elliptical supports adapted to roll upon said base members, each of said arms constituting a straight extension of a radial edge of its curved support, means to support a boat normally upon the upper ends of said arms, the arms and their supports being so arranged as to be held normally in unstable position whereby when the boat is released the arms will swing outwardly and downwardly automatically, and means to secure the boat keel in normal fixed position.

2. In a device of the character set forth, the combination of standards, means to secure the standards in stationary upright position and each including a channel member, a pair of davit arms coöperating with said standards, each of said arms being normally supported in steady position within the standard channel adjacent thereto, an elliptical support for each arm, said support also being housed within the standard channel and standing in unstable position

upon the end of the flatter portion of its curve, means to detachably support a life boat upon the upper ends of the arms, a pair of cables to support the boat when detached from said arms, and means operable from within the boat for controlling the speed of descent thereof.

3. In a device of the character set forth, the combination of a pair of standards, each including an upright member, a base member extending outwardly from the bottom of the standard, a series of brace members coöperating with said base member and said upright, a pair of davit arms coöperating with said standards, each of said arms including an elliptical support adapted to roll upon the adjacent base, means to confine the support to certain positions or movements with relation to the standard, said means including a stud and groove connection between the support and one of said braces, the stud being carried by the support adjacent the end of its flatter curved portion and movable along the slot in approximately a straight path due to the ellipticity of the rolling support, means coöperating with the upper ends of the arm to support a boat therefrom, supplemental supporting means for the keel of the boat, and mechanism to control the speed of descent of the boat.

4. In a device of the class set forth, the combination with a life boat and means for hoisting and lowering the same, of means for normally supporting the keel of the boat in definite fixed position, said keel supporting means including rotary members adapted to engage one face of the keel and pivoted members adapted to coöperate with the other face of the keel, substantially as set forth.

5. In a device of the class set forth, the combination with a life boat and means for hoisting and lowering the same, of means for normally supporting the keel of the boat in definite fixed position, said keel supporting means including a plurality of co-axially arranged rotary cams whereby the boat may be hoisted to final position, each of said cams having a lug engaging against the outer face of the keel, pivoted dogs on the opposite side of the keel, the free ends of said dogs being engaged by the keel while it is moving into final position and said dogs serving to coöperate with said cam lugs to prevent all lateral vibration of the bottom of the boat.

6. In a supporting device for a life boat, the combination of a chair having a hook at its upper end adapted to engage and hold the gunwale of a boat, a plurality of co-axially journaled cams having lugs to engage the outer face of the keel, means to rotate the cams simultaneously, means to hoist the boat causing the gunwale to come into engaging position with respect to said hook,

and a plurality of members pivoted at stationary points independently of the cams and adapted to coöperate with the inner face of the keel.

5 7. In a lifeboat launching device, the combination of supports, a vertical drum shaft, a two-part drum mounted upon said drum shaft, each part of the drum being interlocked with the shaft in its normal position 10 and being adapted to slide upwardly from said position so as to be free to rotate independently of the shaft, braking means secured to the shaft between the drum parts, flexible connections extending between the 15 boat supports and the drum parts, and means to control the rotation of the drum shaft, substantially as set forth.

8. In a lifeboat launching device, the combination of a pair of davit arms, means to 20 support a lifeboat upon said davit arms including flexible connections, a vertical drum shaft, means to control the rotation of the drum shaft, said drum shaft having a pair of polygonal shoulders, two independent 25 drum elements journaled loosely upon said shaft and interlocking normally by the action of gravity with said shouldered portions of the shaft but slideable upwardly for disconnection therefrom for rotation independently of each other, and means to guide 30 said flexible connections to said drum ele-

ments where they are connected at their ends opposite the boat.

9. In a lifeboat launching apparatus, the combination of a pair of rigid standards 35 fixed in stationary position upon a ship, each of said standards comprising a base and a chair portion having an arm extending outwardly toward the side of the ship substantially parallel to the base and spaced upwardly therefrom sufficiently far to receive a lifeboat adjacent the base, a pair of movable davit arms associated with the standards and operating upon the base portions thereof, means to support a lifeboat above 40 the outwardly extending arms, a pair of flexible connections extending from the davit arms for manipulating the lifeboats, power devices for controlling the flexible 45 connections, and means housing the power devices between said standards but at one side or inwardly from the plane common to said standards whereby the power devices may be manipulated without interference 50 with either of said lifeboats. 55

In testimony whereof I have signed my name to this specification in the presence of two subscribing witnesses.

RICHARD TJADER.
